United States Patent Office

Des. 184,521
Patented Mar. 3, 1959

184,521

EDUCATIONAL TOY

Thomas H. Grimes, Wilmette, and Robert J. Meythaler,
Kenilworth, Ill.

Application May 5, 1958, Serial No. 50,748

Term of patent 14 years

(Cl. D34—15)

Figure 1 is a perspective view of the educational toy showing our new design;

Fig. 2 is an exploded view thereof;

Fig. 3 is an enlarged front elevational view of the educational toy shown in Fig. 1;

Fig. 4 is a bottom view of Fig. 3;

Fig. 5 is a top plan view of Fig. 3;

Fig. 6 is a back view of Fig. 3;

Fig. 7 is a right end view of Fig. 3; and

Fig. 8 is a left end view of Fig. 3.

The dominant features of the design are represented in full lines on the drawings.

We claim:

The ornamental design for an educational toy, substantially as shown and described.
